COMPUTING TRAVEL CHART

Ugo Torricelli, New York, N. Y., assignor to
Torricelli Creations, Inc.

Application April 2, 1951, Serial No. 218,745

4 Claims. (Cl. 235—85)

1

This invention relates to a computing travel chart.

The object of this invention is to provide a combination chart and computing board on which the progress of an airplane flight may be indicated and followed, or observed, both as to time and location in its progress from one terminal to the other in its flight.

Another object of this invention is to provide an indicating and computing board of the foregoing character in which provision may be made for the geographical changes in time, so the clock time may be progressively indicated on the chart as the flight progresses.

Another object of this invention is to provide an indicating and computing panel board of the character described above, in which the time may be variably indicated corresponding to the geographical location of various geographical points, such as the major cities over which or through which an airplane flight may pass.

The construction of a preferred embodiment of the invention is shown in the accompanying drawings, in which:

Fig. 1 is a front view in perspective elevation, with parts broken away to show certain details of construction of the card supporting frames, representing selected cities and the numbered hours of a time interval somewhat in excess of one day;

Fig. 2 is a vertical section looking endwise along the line 2—2 in Fig. 1;

Fig. 3 is a horizontal section of a portion of the frame in Fig. 1 taken along the line 3—3 in Fig. 1.

As shown in the drawing, the indicating and computing device 10 comprises an indicating back board 11, a pair of stationary card holding frames 12 and 13, one or more intermediate card holding frames 14 and 15, and a box frame for enclosing the card holding frames and the chart, comprising a base 16 and a cover closure frame 17 fitting snugly over the rim flange 18 on the base 16.

The indicating panel or back board 11 is rectangular in shape, of any suitable lightweight material, such as wood, and is marked or ruled with a series of parallel horizontal lines 21 that are equally spaced vertically and that extend horizontally from near one edge of the indicating panel 11 to the opposite right hand edge of that panel.

The two card holding frames 12 and 13 are fixedly secured to the base panel 11 near the top and bottom ends by simple suitable means such as the screws 22, so the frames 12 and 13 will be

2

substantially vertical, parallel to the two vertical side edges of the indicating base 11, and perpendicular to the horizontal ruled lines 21 on the indicating base panel 11. Those two frames 12 and 13 serve as holders for adjustably movable time indicating cards 23 which may be vertically shifted and adjusted to selected positions to dispose the clock indicating numbers on the card 23 adjacent the respective horizontal lines 21 which are thus to be identified and designated the corresponding clock hour at the corresponding geographical location, as indicated by the identifying card 24. The card 24 is held in an appropriately shaped card holder 25, formed to provide a narrow channel for the top and bottom edges of the card 24 and having inwardly turned flanges 26 and 27. The card holder 25 is suitably mounted and attached to the card holding frame 13, in fixed position. In order to hold the hour-indicating card 23 in selected adjusted position, the frames 12 and 13 are provided with similar inwardly turned flanges 28 and 29 that provided sufficient holding friction against the cards 23 to hold the card against casual displacement after it has been moved to a selected and adjusted position in the card holding frames 12 or 13.

The distance between the card holders 12 and 13 is subdivided percentage-wise by a scale 31 along or near the lower edge of the indicator base 11. As indicated in Fig. 1, the distance between the two frames 12 and 13 is divided by the scale 31 from zero to 100 percent.

As identified by the markers in the card holders 25 of the two card holding frames 12 and 13, those two frames may be marked to identify the terminal points of an airplane flight, and for the purpose of illustration, those two points are shown as New York and Los Angeles. In order to indicate the flight, assuming, for example, a non-stop flight, a line 32 may be drawn by means of a piece of chalk 33 or other easily erasable material between the card holders 12 and 13, between the terminals of the horizontal lines indicating respectively the hour of departure and the projected hour of arrival.

In order to check the schedule of flight against actual flying time and conditions, or to check geographical locations against the projected time of the flying schedule, the intermediate card holders 14 and 15 may be suitably positioned at appropriate spaces between the two terminal frames 12 and 13 to correspond to the flying geographical distances of the considered points relative to the terminal geographical lo-

cation, shown herein by way of example as the cities Denver and Chicago.

The two intermediate movable frames 14 and 15 are provided with pointers 35 at their lower ends, with sharpened front edges, to permit the frames 14 and 15 to be suitably disposed along the bottom percentage scale 31.

The side edges of the movable frames 14 and 15 are similar to the side edges 28 and 29 shown on the stationary frames 12 and 13, in order similarly to hold time indicating cards 23 at appropriate levels to line up the hour numbers properly at the corresponding horizontal lines 21 already previously identified by the hour numbers at the terminal point, shown as New York, for example, making proper allowance for the change in the time at the city represented by the designating card 24 for the associated frame 14 and 15.

In order to hold the indicating base board 11 and the movable card holder frames 14 and 15 in assembled position, the baseboard 11 and the frames are enclosed in a box frame consisting of the back 16 and the border frame 17. As shown in more detail in Fig. 2, the back 16 is provided with the peripheral upstanding flange 18 which serves as a friction border to receive and hold the front closure frame 17, thereby serving as a closed box to hold the base 11 and the card frames 14 and 15 in assembled position, while at the same time providing sufficient space between the front surface of the base 11 and the juxtaposed back surface 17-a of the closure frame 17 to provide a channel space along the top and bottom edges of the closure frame 17 to permit free horizontal sliding movement of the two frames 14 and 15 along the indicator base 11. As shown in more detail in Fig. 2, the top and bottom borders of the movable frames 14 and 15 are of appropriate thickness to substantially fill the space between the front, or top, surface of the indicator base 11 and the rear surface 17-a of the closure or border frame 17.

In order to provide for lightness in weight, the several components of the computing device may be made of light weight material, such as wood or plastic, and the cover frame 17 particularly should be made of plastic in order to expose the figures of the scale 31 along the lower edge of the indicator base 11.

The travel courses may be drawn to show the origin and destination of flight, with stop-overs wherever they occur. Thus, the broken line 32 may represent a flight from New York to Los Angeles, or one leg of a flight from some point in Europe to Hawaii, for example, with stop-overs at New York and Los Angeles. An example of a flight in the reverse direction, with an intermediate stop-over is indicated by the broken line 33.

While the invention has been illustrated in a preferred form of construction, it is to be understood that various changes or modifications may be made in those details of construction without departing from the spirit and scope of the invention as set forth in the appended claims.

I claim:

1. A computing travel chart, comprising a back board having a surface to accept a writing line; two vertical strip-holding frames mounted on the backboard and horizontally spaced to represent terminal points of a distance corresponding to the horizontal spacing between the two vertical frames; a calibration scale on the backboard to subdivide the horizontal spacing between the two vertical frames on a percentage basis; a plurality of equally spaced horizontal lines ruled on

the backboard between the two vertical frames to represent the time of the hours of one day; a card in each frame having the numbers imprinted thereon in sequence corresponding to the twenty-four hours of a day, each card being vertically adjustable in its frame for positioning opposite the hour numbers opposite selected horizontal lines, whereby the difference in time between the represented geographical terminal points may be indicated by the numbers on the cards in the two frames at opposite ends of the respective horizontal lines; and a movable vertical frame provided with a similar hour number card vertically adjustable for proper positioning according to the time relationship of the geographical location represented by the movable frame relative to the hours represented by the horizontal hour lines, whereby time and distance data may be readily computed for a plane flying from one terminal geographical location to the other.

2. A time and distance computing chart for plane travel between two terminal points geographically spaced comprising a rectangular board horizontally lined with equally spaced horizontal lines to represent successive hours for a time interval of the order of one day; a scale parallel to the lines to subdivide the horizontal space between the terminals of the lines on a percentage basis; a movable vertical marker at each end of the lines, the marker being marked with the numbers of the hours of the day, and the hour numbers being spaced according to the line spacing on the board, with each marker representing a geographical location; a supporting frame to hold each marker in its selected vertically adjusted position with the hour numbers adjacent the ends of the lines; and a vertical frame parallel to the two end frames and having a similar marker vertically adjustable therein, and said frame being horizontally adjustable to a selected position between the two end frames.

3. A time and distance computing chart for plane travel between two terminal points geographically spaced, comprising a rectangular board horizontally lined with equally spaced horizontal lines to represent successive hours for a time interval of the order of one day; a scale parallel to the lines to subdivide the horizontal space between the terminals of the lines on a percentage basis; a movable vertical marker at each end of the lines, the marker being marked with the numbers of the hours of a day, and the hour numbers being spaced according to the line spacing on the board, with each marker representing a geographical location; a supporting frame to hold each marker in its selected adjusted vertical position with the hour numbers adjacent the ends of the lines; and a vertical frame parallel to the two end frames and having a similar marker vertically adjustable therein and said frame being horizontally adjustable to a selected position between the two end frames, and the several card frames, said holding frame having the horizontal top and bottom channels for the movable card-holding frame, to permit free horizontal movement of said card-holding frame to selected position intermediate the two end frames.

4. A time and distance computing chart for plane travel between two terminal points geographically spaced, comprising a rectangular board horizontally lined with equally spaced horizontal lines to represent successive hours for a

time interval of the order of one day; a scale parallel to the lines to subdivide the horizontal space between the terminals of the lines on a percentage basis; a movable vertical marker at each end of the lines, the marker being marked with the numbers of the hours of a day, and the hour numbers being spaced according to the line spacing on the board, with each marker representing a geographical location; a supporting frame to hold each marker in its selected adjusted vertical position with the hour numbers adjacent the ends of the lines; and a vertical frame parallel to the two end frames and having a similar marker vertically adjustable therein and said frame being horizontally adjustable to a 15 selected position between the two end frames, and

a holding frame for supporting the ruled board and the several card frames, said holding frame comprising a box base having an upstanding rim flange providing a recess to receive the ruled board with an easily accommodating fit, and a cover frame fitting snugly over the rim flange and dimensioned to provide top and bottom horizontal channel spaces between the inside surface of the cover frame and the front surface of the 10 ruled board, said channel spaces serving to accomodate the top and the bottom ends of the card holding frames and to permit free movement of the intermediate card holding frame.
